United States Patent Office

Des. 222,159
Patented Oct. 5, 1971

222,159

TOY TRUCK

Louis G. Muys and Albert G. Keller, Chicago, Ill.,
assignors to Strombecker Corporation

Filed June 29, 1970, Ser. No. 23,738

Term of patent 14 years

Int. Cl. D21—01

U.S. Cl. D34—15

Fig. 1

Fig. 2

Fig. 3

Fig. 4

Fig. 5

FIG. 1 is a perspective view of a toy truck showing our new design; and

FIG. 2 is a left side elevational view, the right side being a mirror image thereof; and

FIG. 3 is a front elevational view of the truck cab of FIG. 1;

FIG. 4 is a top plan view of FIG. 2; and

FIG. 5 is a rear elevational view of the truck cab of FIG. 1.

We claim:

The ornamental design for a toy truck, as shown and described.
